UNITED STATES PATENT OFFICE.

ADAM CNEESH, OF LOS ANGELES, CALIFORNIA.

DESIGN FOR A TEXTILE FABRIC OR SIMILAR ARTICLE.

Application filed June 6, 1928. Serial No. 27,015. Term of patent 3½ years.

To all whom it may concern:

Be it known that I, ADAM CNEESH, a citizen of Lithuania, residing at Los Angeles, in the county of Los Angeles and State of California, have invented a new, original, and ornamental Design for Textile Fabric or Similar Article, (File No. 808), of which the following is a specification, reference being had to the accompanying drawing, forming part thereof.

The figure in the drawing is a plan view of a piece of textile fabric embodying the design.

I claim:

The ornamental design for a textile fabric or similar article, as shown.

ADAM CNEESH.
